(57) **CLAIM**

The ornamental design for a canine collar clip, as shown and described.

DESCRIPTION

FIG. 1 is a front perspective view of the canine collar clip showing our new design;

FIG. 2 is a back perspective view of the canine collar clip;

FIG. 3 is a front elevational view of the canine collar clip;

FIG. 4 is a back elevational view of the canine collar clip;

FIG. 5 is a right side elevational view of the canine collar clip;

FIG. 6 is a left side elevational view of the canine collar clip;

FIG. 7 is a top plan view of the canine collar clip; and,

FIG. 8 is a bottom plan view of the canine collar clip.

The broken lines in the drawings represent portions of the canine collar clip and form no part of the claimed design.

1 Claim, 6 Drawing Sheets
